UNITED STATES PATENT OFFICE.

AXEL O. NIELSEN, OF RACINE, WISCONSIN, ASSIGNOR TO NIELSEN MACHINE COMPANY,
A PARTNERSHIP COMPOSED OF A. O. NIELSEN AND C. C. NIELSEN, OF RACINE,
WISCONSIN.

JACK.

Application filed January 20, 1926. Serial No. 82,537.

My said invention relates to a jack such as is used for lifting automobiles and the like and it is an object of my invention to provide quickly acting means for raising and lowering heavy objects.

A further object of my invention is to provide quickly acting means for positioning the lifting elements of the jack.

Referring to the accompanying drawings, which are made a part hereof, and on which similar reference characters indicate similar parts,

Figure 1 is a side elevation of my device.
Figure 2, a plan.

Figure 3, a section on line 3—3 of Figure 2, and

Figure 4, a fragment of a modified form of the invention.

In the drawings reference characters 10 indicate intermediate side members of the frame of the jack, said frame carrying a lifting device 11 by means of a lever 12 fulcrumed at 13 on front frame members 14 and pivotally connected at 15 to rod 16. Links 17 are pivotally connected at one end to the lifting device and at the other end to frame members 14, as indicated at 18.

The rod 16 is threaded at its rear end for engagement with an internal thread on a nut 19 provided with peripheral teeth to form a ratchet bearing at its rear side against a block 20, which serves as a support for the ratchet nut. The block is supported by trunnions indicated at 21, which trunnions are mounted for limited oscillation in bearings on the side frame members and said block is provided with a ball thrust bearing (not shown) against which a collar on the ratchet bears for the purpose of reducing friction.

A pair of oppositely facing inwardly-directed pawls 22 are arranged for engagement with the ratchet, these pawls being spring pressed toward the ratchet and being slidable in bearings 23 fixed to hand levers 26 hereinafter described. The bearings are notched at opposite sides adjacent their ends to receive pins 24 on the shafts of the pawls, which shafts are also provided with hand-grips 25, by means of which the pawls may be withdrawn in directions radial to the ratchet and by turning the shafts until the pins 24 are out of engagement with their notches, the pawls may be held out of engagement with the ratchet by the pins

bearing against the outer rims of the bearings and thus holding the pawls away from the ratchets. It is to be noted here that the notches are wider than the pins 24, thus permitting a limited rocking movement, whereby the active faces of the pawls may remain in engagement with the teeth of the ratchet throughout the stroke of the pawls, as hereinafter referred to. It will be evident, also, that the pawls are reversible by turning the hand-grips 25 through arcs of 180°.

For operating the ratchet nut to move the rod lengthwise of the jack, and thus raise or lower the lifter 11 the device of my invention is provided with a pair of hand-levers 26 united at their rear ends by a cross bar (not shown) for engagement by the hand of the operator, to rock the hand-levers up and down about their pivots 27 on the rear set of side frame members shown at 34. This, as will be obvious, causes the pawls to engage alternately with the ratchet nut for rotating it, thus rendering the ratchet double acting. By retracting both the pawls from the ratchet nut and so rendering it inoperative the nut may be turned by hand to bring the rod 16 and the lifter rapidly to any desired position, after which the pawls may be re-engaged with the ratchet.

The frame of the jack is provided near the rear with brackets 29 carrying wheels 30 which are mounted after the manner of casters in vertical bearings 31. At the forward end a shaft 32 is fixed in the front side members, said shaft carrying wheels 33 at its outer ends for supporting the front end of the jack. In the present embodiment of the invention the hand levers 26 are located directly rearwardly of the side frame members 10, the pivots 27 being on the auxiliary side frame members 34, which are bolted to the members 10 by the same bolts which secure the brackets 29 in place. A bridge member 35 may be secured to the auxiliary members 34, or may be made integral as preferred, said bridge member serving to hold the sides of the frame in spaced relation.

One advantage of the device thus far described resides in the fact that it may be very quickly taken apart and re-assembled. For this purpose a pin 36 extends through a socket 37 pivoted at 15 to the lever 12 and through the end of the rod 16 in said socket.

This pin is held in place merely by friction and can readily be forced out of place. Thereupon the rod can be turned to remove it from the ratchet nut and the thrust block 20 and when the rod has been removed the ratchet nut can be lifted out of place, after which the block can also be removed. Another advantage resides in the fact that the trunnions of the thrust block permit the rod 16 to tilt as the lever 12 moves, without causing binding of the rod in said block.

Figure 4 shows a modified form of the invention, only so much being shown as is essential to an understanding thereof. In this form of the invention the socket member 38 is similar to socket member 37 in Figure 1, but has a long thread of rather steep pitch coacting with a like thread on rod 39, these threads being right-hand. A unit 40 on the rod 39 has a left-hand thread coacting with a like thread on said rod 39, and a ratchet 41 is fast to the rod. Pawls (not shown) are actuated to cause rotation of the rod and its operation is like that of the first form except for the reversely-acting screw threads, which impart a more rapid rotation to the rod and thus accelerate the speed of the movement of the parts, as will be readily understood.

It will be obvious to those skilled in the art that various changes may be made in my device without departing from the spirit of the invention and therefore I do not limit myself to what is shown in the drawings and described in the specification but only as indicated in the appended claims.

Having thus fully described my said invention, what I claim as new and desire to secure by Letters Patent, is:—

1. A jack comprising a frame, a lifting device at one end thereof, parallel motion mechanism for said lifting device, a threaded

rod movable lengthwise of the frame for operating said parallel motion mechanism, a ratchet having internal threads engaging the threads of the rod, hand levers on the frame rearwardly from the ratchet, and oppositely acting reversible pawls on the hand levers engaging said ratchet, substantially as set forth.

2. A jack comprising a frame, a lifting device in said frame, a threaded rod movable lengthwise of the frame for operating said lifting device, a ratchet on said rod having threads engaging the threads on the rod, a hand lever pivoted longitudinally of the frame and a dog mounted in socket in a support on said hand lever transversely of the frame and extending inwardly toward said ratchet, said dog being adapted to be reciprocated for rotating the ratchet and adapted to oscillate in its support for maintaining uniform face contact with the coacting faces of the ratchet teeth, substantially as set forth.

3. A jack comprising a frame, a lifting device in said frame, a threaded rod removable lengthwise of the frame for operating the lifting device, a ratchet on said rod adapted to be rotated to move the rod longitudinally of the frame, said ratchet having teeth spaced about its circumference, a lever pivoted longitudinally of the frame and having arms disposed adjacent the periphery of said ratchet, a dog carried by said arms, said dog extending inwardly and engaging said ratchet teeth, substantially as set forth.

In witness whereof, I have hereunto set my hand and seal at Washington, District of Columbia, this twentieth day of January, A. D. nineteen hundred and twenty-six.

AXEL O. NIELSEN. [L. S.]
